UNITED STATES PATENT OFFICE.

JOHN REICHERT, OF RACINE, WISCONSIN.

BREAST-STRAP SNAP-HOOK AND THE LIKE.

1,170,846.

Specification of Letters Patent.

Patented Feb. 8, 1916.

Original application filed May 22, 1911, Serial No. 628,798. Divided and this application filed January 16, 1915. Serial No. 2,611.

To all whom it may concern:

Be it known that I, JOHN REICHERT, a citizen of the United States, residing at Racine, in the county of Racine and State 5 of Wisconsin, have invented certain new and useful Improvements in Breast-Strap Snap-Hooks and the like, of which the following is a specification, this application being filed as a division of Patent No. 1,125,397, granted 0 to me January 19, 1915, on my application filed May 22, 1911, Serial No. 628,798.

This invention comprises certain improvements in and relating to breast strap connectors and the like; and the objects and 5 nature of the invention will be readily understood by those skilled in the art in the light of the following explanation of the accompanying drawings illustrating what I believe to be the preferred embodiment 0 from among other formations and arrangements within the spirit and scope of my invention.

An object of the invention is to provide a breast strap connector with an improved 5 formation, arrangement and construction for the connection of a martingale or other part thereto.

The invention consists in certain novel features of construction and in combinations 0 and arrangements as more fully and particularly set forth hereinafter.

Referring to the accompanying drawings:—Figure 1, is a perspective view of a combined breast strap snap and slide constructed in accordance with my invention, the slide in this instance, embodying a roller. Fig. 2, is a perspective view, the martingale loop and the securing pivot being shown separated from the snap and slide yoke.

In the construction illustrated, the snap and slide comprises a snap hook having a shank 1, the hook bill 2, of which is guarded by spring actuated pivotal guard 3. The shank is formed integral with and depends 5 from a yoke carrying the slide which in this instance is formed by a roller. This yoke embodies a cross head 4, from which the shank centrally depends and upwardly extending arms 5, usually parallel, and projecting upwardly from the outer ends of the cross head. A roller 6, extends between the upper ends of the arms or uprights 5, and

is journaled therein or otherwise confined thereto to rotate on a suitable axis, the arm ends being provided with transverse openings for this purpose. This roller is usually parallel with the lower end 4 of the yoke and is spaced a distance therefrom as will be well understood by those skilled in the art.

The yoke is provided with a martingale loop 7, pivotally joined thereto to swing vertically, a suitable loose or pivotal coupling being provided for this purpose, and this coupling is preferably located at a lower corner of the yoke, and preferably removably unites the loop to the yoke.

In the construction illustrated, the martingale loop is arranged transversely with respect to the yoke and is formed with a side opening, or in other words the loop is split and provided with a pair of separated laterally projected ends, ears or eyes 70, having alined perforations to receive a pivot pin or screw 8. These ears 70, are spaced apart a distance so as to receive between them a corner portion of the yoke through which said pivot is passed. I show the opposite corner portions of the yoke formed to fit between said ears of the loop and provided with perforations 80, for the passage of said pivot. Both corners of the yoke can be so formed and perforated to permit application of the loop to either corner desired thereby rendering the combined device reversible, although my invention is not so limited. The pivot is preferably in the form of a headed machine screw passing loosely through one eye 70, and through the perforation 80, and screwing into the other eye 70, which can be tapped or screw threaded for this purpose.

By thus employing a loop of this construction with removable means for coupling the same to the yoke, the loop can be readily removed from one corner of the yoke and applied to the other corner without interfering with the roller 6, or other parts of the device, and furthermore, peculiar advantages are attained by employing a removable loop with separated attaching ends or a side opening, inasmuch as the loop when so formed can be passed through a previously sewed loop formed at the end of the martingale and can be detached there-

from when the martingale is to be separated from the snap hook. By employing such arrangement and formation of loop, previously sewed martingales can be readily attached to and detached from the snap hooks when constructed in accordance with my invention, as will be understood by those skilled in the art.

It will be understood by those skilled in the art, that when the devices illustrated, are in use applied to harness, the martingale loops extend upwardly at a rearward inclination from the pivots joining them to the breast strap and yoke connectors.

I have so located the martingale loop with respect to the various elements of the breast strap and yoke connector, as to perform the desired function of attaching the martingale, yet without interfering with the proper functions and operation of said various elements of the connector. I have entirely removed the martingale loop from the shank or stem of the snap hook so as to allow free play of said hook without interference from or by the martingale and yet so as not to prevent or interfere with the free and proper movement of the slide on the breast strap. The martingale loop is so located, as hereinbefore described, as to exert its direct upward pull approximately longitudinally of the snap hook and without exerting lateral pull on the hook or on the yoke or slide and without tending to twist the connector and cause lateral wear and cutting of straps connected therewith.

The various loops are so attached to the snaps that the strain of the loops on the snaps will not interfere with the proper working and operation of the snaps in connection with the breast straps and yokes and will not cause the breast strap slides to twist or unduly bear on the breast strap, and so that said loops do not in any way interfere with the snap hook guards and the easy operation thereof. The loops can be readily attached to and removed from the snap hooks and the arrangement is such that the snap hook can be used without the loop, that is, that the provision for the attachment of the loop does not in any way interfere with the operation of the snap hook whether or not the loop is employed, and the loop can be applied to or removed from either side of the snap hook without detaching the snap hook or any of the essential parts thereof, and the loop can be as readily removed from and inserted in the sewed end of a martingale without cutting the stitching or in any way interfering with the formation of the martingale.

Provision is made for attaching the loop at the proper position with respect to the snap hook and the part receiving the breast

strap so as to properly distribute the strain of the martingale on the breast snap slide 6 or roller and the snap hook. For instance, it will be noted that the loop is arranged between the breast strap receiving yoke and the bill of the snap hook close to or attached at the cross head at the upper end of the 7 snap hook, and that the loop extends laterally beyond the hook and yoke and is free to swing vertically.

What I claim is:

1. A combined breast strap snap and 7 slide consisting of a vertically-disposed yoke provided with a depending hook comprising a shank and a spring guard, a freely and vertically swingable martingale loop, and a removable coupling pivotally and removably joining said loop to the yoke approximately at a lower corner thereof and spaced a distance from the upper end of the shank and guard of the hook, the said loop being arranged to extend beside said yoke to exert 8 upward pull on and approximately longitudinally of said hook, as and for the purposes substantially as described.

2. A breast strap snap and slide consisting of a yoke and a depending snap hook, the yoke being laterally enlarged with respect to the hook and having a transverse opening located approximately at a lower corner of the yoke, a vertically swingable loop coupled to the yoke at said opening, and a removable pin forming the axis on which said loop swings and removably coupling the loop to the yoke, substantially as described.

3. A combined breast strap snap and slide consisting of a yoke provided with a snap hook depending centrally from the lower cross bar of the yoke, said yoke approximately at a lower corner thereof having a transverse perforation, a split martingale loop having rearwardly extending ears straddling the yoke at said perforation, and a removable pivot passing through said ears and said perforation and pivotally coupling the loop to the yoke, so that said loop can swing up beside said yoke to exert upward pull approximately longitudinally of said hook, substantially as described.

4. A combined breast strap snap and slide consisting of a yoke and a snap hook depending from the central portion of the lower cross bar of the yoke, said yoke formed with a transverse perforation approximately at a lower corner thereof, and a vertically swingable martingale loop having rearwardly extending ears straddling said yoke at said corner and pivotally joined thereto, a pivot being provided passing through said perforation.

5. A combined breast strap snap and slide consisting of a yoke having a hook depending from the central portion of its lower

cross bar, said yoke having transverse perforations at its lower corners, a removable vertically swingable loop having a pair of ears adapted to removably straddle either 5 corner of the yoke, and a removable pivot adapted to pass through said ears and either perforation.

In testimony whereof I affix my signature in presence of two witnesses.

JOHN REICHERT.
